UNITED STATES PATENT OFFICE.

JAMES W. HAMMETT, OF EUREKA, WEST VIRGINIA.

FENCE.

SPECIFICATION forming part of Letters Patent No. 580,311, dated April 6, 1897.

Application filed August 29, 1896. Serial No. 604,295. (No model.)

To all whom it may concern:

Be it known that I, JAMES W. HAMMETT, of Eureka, in the county of Pleasants and State of West Virginia, have invented a new and 5 useful Improvements in Fences, of which the following is a specification.

The object of my invention is to provide a construction of wire fence which shall increase the strength and stiffness of the same 10 and which shall adapt it to firmly stand upon a hillside and be capable of easy repair in case a post should lose its hold in the ground due to the caving or washing of the bank or hillside; and it consists in the peculiar construction and arrangement of a brace-panel 15 and a hillside-post, as hereinafter fully described.

Figure 1 is a perspective view of my brace-panel; Fig. 2, a side view of the hillside-post shown fastened in the earth. Fig. 2^a is a horizontal section through the same, and Fig. 2^b is a detail of the fastening-staple; Fig. 3, a detail side view of the stay-strip, and Fig. 4 a view of these three features incorporated 25 in a fence.

Referring to Fig. 1, the brace-panel consists of three posts A A A, two reversely-inclined braces B B', a cap-strip C on the top of the posts slightly inclined in transverse 30 section, so as to shed water, and a horizontal stringer D, secured to the sides of the posts at the top along and under the edge of the cap C. The posts are preferably about four inches square and have an iron foot or base 35 a bolted or riveted to them, by which they are firmly anchored in the ground. The diagonal braces B B' are nailed to opposite sides of the posts, and the one, B', which is intended chiefly to take the strain off the fence, is about 40 four inches square and gained or mortised into the posts, the posts and the brace being each notched out where they fit together, so as to make a strong and stiff joint. The other brace, B, is simply a heavy board nailed on the 45 opposite side after the wires are put on. The cap and stringer are simply fencing-boards nailed one on top of the posts and the other on the sides of the posts immediately under the cap.

50 The bank and hillside post E, Fig. 2, is preferably made of material four inches square, whose lower end is provided with a firmly-at-

tached and wedge-shaped iron foot e, through which latter there is an oblong vertical slot e', adapted to receive two stakes or pins e² e², 55 which are driven into the bank with a reversed inclination, so as to get a firm hold or anchorage to immovably secure the lower end of the post. To this post on the higher side of the hill is riveted a heavy bracket-shaped bar F, 60 whose angle is bent to conform to the surface of the ground and assist in holding the post vertical. This bar is also provided with an oblong slot f, adapted to receive two pins or stakes f' f', driven at a reversed inclination 65 into the ground to give an anchorage therein, and has also a brace-rod f² extending from the outer end of this bar F to the upright post, to which it is secured by a nail, screw, or bolt. The post is provided on the side against which 70 the wires lie with a vertical series of bored holes g, extending about three-quarters of the way through the post, and over the face of each hole is placed a washer g', through which the wire w of the fence is driven in the form 75 of a loop with a suitable punch and secured by a staple s of the proper length, which when driven in the bottom of these holes straddles the wire and goes through to the other side of the post and is clenched, as shown in Fig. 80 2^a. This is a very desirable connection in case the bank should cave and a particular post should be moved back, as the slack of the loop in the wire can be let out to provide for the extra length required by moving back 85 the post, or more slack can be taken up, if the line is shortened, without cutting the wire or moving any other part of the fence. The object of the washer is merely to form a bearing for the wire and prevent its tension from 90 involving a splitting strain on the post.

The stay-strip, Fig. 3, consists of a piece of wood three inches wide and one and one-fourth inches thick and of sufficient length to reach from the bottom of the fence to the top. This 95 strip is secured to the wires between posts to act as a stay, and it is secured to the wires by a washer and a staple without a depression or by a staple and depression without a washer, 100 as may be desired.

The staple is made of wire with flat sharp chisel-shaped edges as wide as the wire is thick, and when driven should be placed diagonally on the timber, so that the edges stand

directly across the grain of the wood, the edges being made at an angle with the arch of the staple, as shown in Fig. 2^b.

In setting up this fence the various features 5 are assembled as shown in Fig. 4.

Having thus described my invention, what I claim as new, and desire to secure by Letters Patent, is—

1. A brace-panel for a wire fence, comprising 10 vertical posts with iron anchorage feet or braces, an inclined brace-bar crossing the posts diagonally and gained or notched reciprocally into each other, a reversely-inclined bar or board on the wire side of the posts, and 15 a cap-strip and stringer substantially as and for the purpose described.

2. A hillside or bank post comprising a vertical post with wedge-shaped metal foot hav-

ing a transverse slot through the same combined with pins or stakes driven through said 20 slot from the exterior entirely through the foot into the hillside substantially as and for the purpose described.

3. A hillside or bank post comprising a vertical post with a wedge-shaped metal foot having 25 a slot through the same, an angular surface-bracket having one end attached to the post and the other end slotted to receive anchorage-pins, and a diagonal brace extending from the surface-bracket to the post substantially as and for the purpose described. 30

JAMES W. HAMMETT.
